HUGO E. GRIESHABER, OF NEW LONDON, CONNECTICUT, ASSIGNEE TO ELECTRIC BOAT COMPANY, OF NEW YORK, N. Y., A CORPORATION OF NEW JERSEY.

SUBMARINE BOAT.

1,187,522.

Specification of Letters Patent. Patented June 20, 1916.

Application filed July 23, 1915. Serial No. 42,264.

To all whom it may concern:

Be it known that I, HUGO E. GRIESHABER, a citizen of the United States, residing at and whose post-office address is New London, county of New London, and State of Connecticut, have invented certain new and useful Improvements in Submarine Boats; and I do hereby declare the following to be a full, clear, and exact description of the invention, such as will enable others skilled in the art to which it appertains to make and use the same.

This invention relates to the construction of submarine boats and more particularly to ventilating devices for use in connection with such boats.

The invention involves the provision of a ventilating tube projecting upwardly from the hull of a submarine boat and adapted for use both in supplying fresh air to the interior of the boat and permitting the exhaust of foul air from the boat, the tube having protective devices associated therewith whereby the entrance of water through the ventilator to the interior of the boat is effectively guarded against under all conditions. In combination with the tube, means are employed whereby excessive pressure conditions within the boat, occurring as a result of the existence of extraordinary conditions, are instantly and automatically relieved.

The outer end of the ventilating tube is protected by a suitable inclosing structure which is provided with an opening located at a distance from the outer end of the ventilator tube. This inclosing structure may, if desired, be a portion of the structure of the boat itself, such for instance as the non-water-tight superstructure ordinarily provided upon the hull of the boat and extending practically throughout the length thereof. If desired, the sheers forward and aft of the conning tower of the boat may be employed as the inclosing structure for the outer end of the ventilator tube or tubes. In the preferred embodiment of the invention, a ventilator tube is provided extending upwardly from the hull of the boat into the space within the sheers and open at its upper end. Directly over this upper end of the ventilator tube an opening is provided in the wall of the sheers. In order to close and open the passage through the ventilator tube, a valve-member is provided

adapted to coöperate with the upper end of the ventilator tube and movable from within the boat to a position in which it closes the ventilator tube or to a position in which it opens the passage through the tube and closes the opening in the sheers above referred to. Another opening is provided in the inclosing structure for the outer end of the ventilator tube and this opening is unobstructed at all times and is located at a distance from the outer end of the tube. Such an opening may be provided by one or more scuppers in the base of the sheers or in the superstructure, the interior of which is in open communication with the inferior of the sheers.

I have illustrated the preferred embodiment of my invention in the accompanying drawings, in which—

Figure 1 is a transverse section through the upper portion of the hull of a submarine boat and the superstructure and sheers showing my improved ventilating devices combined therewith. Fig. 2 is a longitudinal section of the ventilating devices broken away in part; and Fig. 3 is a view corresponding to a portion of Fig. 2 and illustrating a modification of the construction which may be employed.

Referring to these drawings, 4 indicates the hull of a submarine boat and upon this is erected the usual superstructure 5, this being non-water-tight by reason of the provision of scuppers near the base thereof at intervals throughout the length of the boat. The boat is provided with a conning tower as usual and extending fore and aft from this conning tower are the sheers 6. The ventilator consists of a tube 7 extending through the hull of the boat and upwardly therefrom. The outer end of this ventilator tube is inclosed so as to preclude the entrance of water into the tube when the passage through the tube is open. Any suitable inclosing structure may be employed for this purpose, such for instance, as the superstructure of the boat, but I have found it highly convenient and desirable to employ the sheers as the inclosing means. The ventilator tube 7 is therefore shown as extending upwardly from the hull of the boat into the sheers 6. The hull 4 is provided with a suitable opening shaped to receive a casting 8 which is flanged as shown at 9 to facilitate securing it to the hull 4. On

the upper face of this casting is a circular boss 10 which receives the lower end of the ventilator tube 7, the lower end of the tube being secured within the boss 10 by a watertight joint. The tube 7 extends upwardly to a point a short distance below the top wall of the sheers 6 and that wall has an opening therein directly over the end of the tube 7 and of approximately the same size as the tube 7.

At the upper end of the ventilator tube is a valve-member 11 which is movable vertically from within the hull of the boat so as to cause it to close the passage through the tube 7 or to open that passage and close the opening in the top of the sheers 6. The valve-member 11 is provided with gaskets 12 upon its upper and lower faces and its lower face is adapted to engage the upper end of tube 7. The upper face of the member 11 is adapted to engage the ring 13 of a casting 14, shaped to facilitate securing it to the upper end of tube 7 and to the overlying wall of the sheers. The valve-member 11 is mounted upon the upper end of a rod 15 which passes through and is guided by a spider 16 secured within the tube 7. At its lower end, the rod 15 passes through a suitable stuffing-box 17 in the wall of the casting 8, and its lower end is connected to an operating handle 18 pivotally mounted upon the casting 8.

A second means is provided for controlling the passage through the ventilator tube 7, this second means being located within or close to the hull of the boat. In the present instance, a second valve-member 19 is shown within the casting 8 mounted upon a shaft 20, so that it can be moved to the open position shown in Fig. 2, or to the closed position shown in Fig. 3. In the latter position, the valve engages a lip 21 formed about the outlet opening in the wall of the casting 8. From this outlet opening, a conduit 22 leads to any desired point within the boat. The shaft 20 extends through an opening in the casting 8 and is provided with an operating handle 23.

It will be noted that the inclosure for the outer end of the ventilator tube is provided with an opening located at a distance from the end of the tube. In the present instance, the space within the sheers is shown as in open communication with the space within the superstructure 5, so the opening referred to consists of the scuppers shown at 24 in the wall of the superstructure.

When the boat is proceeding upon the surface of the sea, the valve-member 11 is moved to the upper position in which it is shown in Fig. 2, and the auxiliary valve-member 19 is moved to the open position shown in that figure. The passage through the ventilator is therefore open. The opening in the sheers overlying the venti-

lator tube is closed by the valve-member 11. However, air may enter the space within the sheers freely through the scuppers of the superstructure, and such air may pass down through the ventilator tube to the interior 70 of the boat. Obviously, it will be practically impossible for waves or spray to cause water to follow this path for air and thus enter the interior of the boat. When the boat is to be submerged, the valve-member 11 is 75 moved by manipulation of the handle 18 to the lower position in which it coacts with and closes the upper end of the ventilator tube 7, and when the boat is submerged, the space within the sheers is filled by water entering 80 through the scuppers of the superstructure and the opening in the top wall of the sheers. The pressure of this water upon the upper surface of the valve-member 11 aids in holding the latter tightly upon its seat 85 on the upper end of the tube 7. At the same time, the valve-member 11 is free to be lifted from its seat by air pressure on the under side thereof. If the pressure conditions within the boat were to rise to a dangerously 90 high point, a predetermined excess of the air pressure on the under side of the valve-member 11 over the pressure of the water upon the upper side of the valve-member, would cause raising of the valve sufficient to relieve such excessive pressure conditions. 95

It will be noted that the provision of the second valve-member 19 at the base of the ventilator tube permits of closing the passage for the entrance of air in case the sheers 100 and ventilator tube were carried away.

In some instances, it is preferred to make provision for locking the valve-member 11 in its upper or lower position. This may be done by providing the shaft of the valve-member with a thread coacting with a thread in the wall of an opening in the casting 8, as is shown at 25 in Fig. 3, and a hand wheel 26 is then provided upon the lower end of the rod 15. With this construction, the valve-member 11 may be readily moved to one or the other of its operative positions by turning the handle 26. If desired, the valve-member may be mounted upon the end of the rod in such manner as 115 to permit of turning of the rod independently of the valve-member.

While I have illustrated the embodiment of my invention which I prefer to employ, I wish it understood that the invention is 120 not limited to the construction illustrated but that on the contrary, various changes in the construction may be made without departing from the spirit of the invention. In particular, I wish it understood that the 125 invention is not limited with respect to the character of the inclosure employed for the outer end of the ventilator tube, for while I have found it convenient and desirable to employ the sheers as the inclosing structure, 130

I may likewise employ the superstructure of the boat or some other inclosing structure specially provided for use in conjunction with the ventilator tube.

5. What I claim is:

1. In a submarine boat, the combination of a hull, a ventilator leading to the interior thereof, an inclosure for the outer end of the ventilator having an opening there-
10 through, a valve-member and means for moving the valve-member to close the passage through the ventilator or to open that passage and close said opening through the inclosure, said inclosure having a second
15 opening therethrough which is distant from the outer end of the ventilator; substantially as described.
2. In a submarine boat, the combination of a hull, a ventilator projecting therefrom and communicating with the interior of the hull, a structure mounted on the hull and inclosing the portion of the ventilator outside the hull and having an opening there-
20 through, a valve-member and means oper-
25 able from within the boat for moving the valve-member to close the passage through the ventilator or open that passage and close the opening through said structure, said structure having a second opening there-
30 through adjacent to the hull of the boat; substantially as described.
3. In a submarine boat, the combination of a hull, a ventilator projecting therefrom, a structure mounted on the hull and in-
35 closing the portion of the ventilator outside the hull, said structure having an opening therethrough adjacent to the end of the ventilator, a valve-member and means oper-
40 able from within the boat for moving the valve-member into engagement with the end of the ventilator and for moving it away

from the ventilator and into engagement with said structure to close said opening therethrough, said structure having a second opening therethrough which is distant 45 from the end of the ventilator; substantially as described.

4. In a submarine boat, the combination of a hull, a ventilator projecting therefrom, a structure mounted on the hull and in-
50 closing the portion of the ventilator outside the hull and having an opening there-
55 through, a valve-member and means oper-
able from within the boat for moving the valve-member to close the passage through the ventilator or open that passage and close the opening through said structure, said structure having a second opening there-
60 through adjacent to the hull of the boat, and said member being also adapted to be moved to open the passage through the ventilator by pressure of the air within the boat; substantially as described.

5. In a submarine boat, the combination of a hull, a ventilator projecting therefrom, a structure mounted on the hull and in-
65 closing the portion of the ventilator outside the hull and having an opening there-
70 through, a valve-member and means oper-
75 able from within the boat for moving the valve-member to close the passage through the ventilator or open that passage and close the opening through said structure, and a second valve-member operable from within the boat to close and open the pas-
80 sage through the ventilator, said structure having a second opening therethrough which is distant from the end of the ventilator; substantially as described.

In testimony whereof I affix my signature.

HUGO E. GRIESHABER.
